UNITED STATES PATENT OFFICE.

JOHN C. FORSTER, OF PITTSBURG, PENNSYLVANIA.

DESIGN FOR A PUZZLE MEMBER.

SPECIFICATION forming part of Design No. 35,115, dated September 17, 1901.

Application filed June 14, 1901. Serial No. 64,591. Term of patent 14 years.

To all whom it may concern:

Be it known that I, JOHN C. FORSTER, a resident of Pittsburg, in the county of Allegheny and State of Pennsylvania, have invented and produced a new and original Design for a Puzzle Member; and I do hereby declare the following to be a full, clear, and exact description thereof, reference being had to the accompanying drawing, in which a perspective view of a puzzle member embodying my design is shown.

The leading feature of the design consists in a puzzle member having the shape and form substantially as herein shown and described.

As illustrated in the drawing, 1 represents the puzzle member, which is composed of the main portion 2, having the crescent-shaped portion 3 thereon, and from the inner circular edge 4 of the crescent-shaped portion 3

two lugs or prongs 5 extend out therefrom, ²⁰ having rounded ends 6 thereon. Holes 7 are formed in the rounded ends 6 for rings 8, which also pass through holes 9, formed in the rounded ends 10 of a horseshoe-shaped portion 11. ²⁵

What I claim as my invention, and desire to secure by Letters Patent, is—

The design for a puzzle member, substantially as herein shown and described.

In testimony whereof I have hereunto set ³⁰ my hand, at Pittsburg, in the county of Allegheny and State of Pennsylvania, this 8th day of June, 1901.

JOHN C. FORSTER.
